PILLOWCASE OR SIMILAR ARTICLE

Harry Beidelman, New York, N. Y., assignor to Pepperell Manufacturing Company, Boston, Mass., a corporation of Massachusetts

Application May 2, 1957, Serial No. 45,973

Term of patent 7 years

(Cl. D92—26)

Fig. 1.

Fig. 2.

Fig. 1 is a top plan view of a pillowcase showing my new design, portions being broken away for convenience of illustration, and

Fig. 2 is a detail plan view, on a relatively enlarged scale, of a portion of the border design. The border is repeated in regular succession around the open end of the pillowcase, a complete unit thereof being depicted between the lefthand edge and the broken line near the righthand edge.

The characteristic feature of the design resides in the border portion shown in full lines.

I claim:

The ornamental design for a pillowcase or similar article, as shown and described.
